DESIGN FOR A HANDBAG

Louis Flaxman, Baltimore, Md.

Application July 7, 1944, Serial No. 114,331

Term of patent 7 years

(Cl. D87—3)

To all whom it may concern:

Be it known that I, Louis Flaxman, a citizen of the United States, residing at Baltimore, in the county of Baltimore and State of Maryland, have invented a new, original, and ornamental Design for a Handbag, of which the following is a specification, reference being had to the accompanying drawing, forming part thereof.

The opposite side and end are identical to those shown.

I claim:

The ornamental design for a handbag, as shown and described.

LOUIS FLAXMAN.
